TOOL KIT

Paul A. Kegevic, Springfield, Mo.

Application August 10, 1954, Serial No. 448,805

2 Claims. (Cl. 206—16)

My invention relates to improvements in tool kits. An important object of the invention is to provide a tool kit for holding tools and replacement parts, and separating them in arranged order, and providing ready access for their removal and replacement.

A further object of the invention is to provide a plurality of pivoted units for holding tools or the like, which units may be turned to different positions, like the leaves of a book, to provide ready access to the tool holding means carried thereby.

A further object of the invention is to provide frames carrying the tool holding means, which frames are detachably mounted within the case, for their ready removal and return from and to the case.

A further object of the invention is to provide main pockets carried by the pivoted supporting frames, which main pockets serve to prevent accidental separation of the supporting frames from the case.

A further object of the invention is to provide a housing for removably receiving drawers or trays and having a resilient part to exert a yielding pressure upon the drawers to prevent rattling or displacement of the drawers.

A further object of the invention is to provide simple means for attaching the housing and the supporting frame brackets with the case.

Other objects and advantages of the invention will be apparent during the course of the following description.

In the accompanying drawings forming a part of this application and in which like numerals are employed to designate like parts throughout same,

Figure 1 is a perspective view of the tool kit, in the open position,

Figure 2 is a side elevation of the tool kit closed,

Figure 3 is an end elevation of the tool kit closed,

Figure 4 is an end elevation of the supporting frames of the tool carrying means, and associated elements, the supporting frames being shown in the closed vertical position,

Figure 5 is a side elevation of the same,

Figure 5a is a longitudinal section taken on line 5a—5a of Figure 5,

Figure 6 is a horizontal section taken on line 6—6 of Figure 5,

Figure 7 is a vertical section taken on line 7—7 of Figure 5,

Figure 8 is a perspective view of the housing which holds the drawers, and,

Figure 9 is a perspective view of one of the brackets carrying the supporting frames.

The numeral 10 designates a case, which may be formed of leather, plastics material or the like. This case includes case sections 11, connected by a bottom 12, and the connection is flexible so that the case sections may be swung to opened and closed positions. The case sections are detachably connected at their edges by a sliding fastener 13 of any well known or preferred type. The case sections 11 have handles 14 suitably secured thereto, near their tops, as shown.

2

Disposed inwardly of and above the bottom 12 of the case, is a housing 15, see more particularly Figure 8. This housing is preferably formed of metal and includes a horizontal bottom 16, a side 17, and top 18. The side 17 is vertically arranged and the top 18 is generally horizontal but is slightly inclined, preferably extending downwardly toward the side 17, although the top 18 may be inclined toward its free end. The bottom 16, side 17 and top 18 are preferably formed from a single metal sheet, and the top 18 is resilient. Formed integral with the side 17 are ends 19, which are separate from the bottom 16 and top 18, the side of the housing opposite the side 17 is open.

The bottom 16 is formed to provide depending tubular bosses 20, having closed ends 21, which are apertured 15 for receiving bolts or screws 22, having nuts 23, mounted within the tubular bosses 20. The numeral 24 designates angle brackets, including horizontal bases 25, and upstanding sides 26, disposed at right angles to the bases. These brackets are rigid and may be formed of metal. The bases 25 are formed to provide depending tubular bosses 27, for receiving the bosses 20, and the bosses are apertured to receive the bolts or screws 22, the apertures being formed in the closed ends 28 of the bosses 27. As more clearly shown in Figures 4, 5 and 7, the brackets 25 are arranged near the ends 19 of the housing and the sides 26 are spaced slightly from these ends. The bases 25 have their bosses 27 mounted upon the bottom 12, and the bolts or screws rigidly secure the bosses 20 and 27 and their associated elements to the bottom 12. There are 30 of course two pair of bosses 20 and two pair of bosses 27.

The numeral 29 designates inverted U-shaped supporting frames, which are stiff and resilient, and may be formed of metal rods. Three of these frames have been shown for the purpose of illustration, although the number 35 may be varied. Each frame 29 includes an end 30 and arms 31. At their lower ends, the arms are bent to form inwardly directed horizontal extensions 32, which are pivotally and removably mounted within openings 33, formed in the sides 26. The frame sides 31 may be bent 40 outwardly slightly for removing the extensions 32 from the openings 33 or for inserting such extensions into these openings, and the frame sides 31 are resilient and tensioned to swing inwardly toward the sides 26 of the brackets.

The numeral 34 designates large slip-over pockets, to 45 be removably mounted upon the supporting frames 29. Each slip-over pocket may be flexible and is preferably formed of fabric and includes sides 35, closed ends 36 and a closed top 37. The slip-over pockets have a proper length so that they fit fairly snugly upon the sides 31 of the supporting frame. The inner ends 38 of the slip-over 50 pockets are open.

Each slip-over pocket is provided upon its opposite sides with two holding elements 39, which may be in the form of loops, pockets, or other holding elements, arranged vertically or horizontally. These two holding elements will vary in shape, size and arrangement, depending upon the tools which they are designed to hold. It is thus seen that each slip-over pocket 34 and its frame 29 constitutes a tool carrying support or panel, adapted to be turned like a page of a book between the case sections 11, when the latter are extended longitudinally upon opposite sides of the bottom 12, and in the same plane as the bottom, Figure 1.

Removably mounted within the housing 15, are drawers or trays 40, adapted to be arranged in stacked relation. Each drawer has a cover 41, hinged thereto at its rear end, as shown at 42, and a pull element or ring 43 is pivotally mounted upon each cover 41, at its forward edge. Each drawer or tray 40 is provided with compartments 44, Figure 6, which may vary in size and arrangement, depending upon the replacement articles that they are designed to receive.

As is well known, mechanics who do repair work in offices or the like, carry their tools and replacement parts with them. The mechanic having the present tool kit with him, upon arriving at his place of work, opens the case, as shown in Figure 1, and access is had to the various tools carried by the opposite sides of the slip pockets 34. These tools are ordinarily arranged in proper order in the holding elements carried by the slip pockets, and after the tools have been used, they are returned to their corresponding holding elements. The arrangement 10 of the slip pockets 34 and the supporting frames 29 is such that the slip pockets may be moved or swung like the leaves of a book. The slip pockets or tool carrying panels 34 may thus be swung to lie flat upon either case section 11, when the case sections are opened, Figure 1, and the individual drawers 40 at this time may slide through the open side of the housing 15 for removal, above the adjacent case section 11 which is now in the plane of the bottom 12. A selected drawer or tray 40 may be removed from the housing 15 and its cover opened, so that the desired replacement part may be had. The drawer or drawers 40 are returned to the position within the housing 15, and these drawers are in stacked relation, and the lowermost drawer bears 20 against the bottom 16, and the uppermost drawer will bear against the top 18. Since this top is slightly inclined, and the top is resilient, there will be some wedging action between the uppermost drawer and the top 18, and this will cause the several drawers to have clamping engagement with each other, to prevent accidental displacement, rattling or the like, but the drawers may of course be removed when desired by the operator pulling upon the ring or rings 43. The average mechanic ordinarily has one set of tools, and upon return to the shop, the mechanic can separate the supporting frames 29 from the brackets 24 and mount these supporting frames upon similar brackets secured to a bench, shelf or the like. These supporting frames carry the slip pockets, which in turn are provided with the tool holding elements. Hence the tools may be removed from the tool holding elements, and again returned thereto. The frames 29 may again be applied to the brackets 24, the sides 31 being resilient so that the extensions 32 may be inserted into the openings 33. The slip pockets 34 fit 30 fairly snugly upon the supporting frames 29, and when the holding elements 39 carry the tools, this snug fit is increased. The slip pockets therefore oppose the outward movement of the upper portions of the sides 31 of the supporting frame, thereby preventing accidental removal of the pivot extensions 32 from within the openings 33, but the lower ends of the sides 31 may still be flexed to effect the separation, and if desired, the slip pockets can be adjusted upwardly upon the supporting frames. 40

It is to be understood that the form of my invention herewith shown and described is to be taken as a preferred example of the same and that various changes in the 50

shape, size and arrangement of parts, may be resorted to, without departing from the spirit of my invention or the scope of the subjoined claims.

Having thus described my invention, I claim:

1. A tool kit comprising a case including a bottom and a pair of companion case sections hingedly secured to opposite side edges of the bottom, said case sections being swingable to opposed generally parallel positions substantially at right angles to the bottom and extending above the bottom, means carried by the case sections for securing them in their last-mentioned positions for closing the case, the case sections also adapted to lie substantially in the plane of the bottom in longitudinally extended relation beyond said opposite side edges of the bottom when the case is opened, a drawer housing mounted upon and secured to the bottom between the case sections and having an open side facing longitudinally of the adjacent case section when such case section is in the plane of the bottom, a plurality of drawers mounted within the drawer housing in stacked relation and removable therefrom through said open side of the housing longitudinally of and above said adjacent case section when the case section is in the plane of the bottom, the adjacent case section engaging the drawers and preventing their movement from the housing when the case sections are secured together in opposed substantially parallel relation, and a plurality of tool carrying panels pivotally connected with the bottom and swingable toward and from the case sections longitudinally thereof and adapted to lie upon either case section when the latter are in the plane of the bottom, said panels having lower edges terminating a substantial distance above the bottom so that the panels may clear the top of the drawer housing when swung from one case section toward the other, the case sections maintaining the panels in side by side substantially parallel relation above the housing and between the case sections when the case is closed.

2. A tool kit according to claim 1, wherein each of said tool carrying panels is a wire frame having sides pivotally connected with the bottom, a slip-over flexible pocket mounted upon the wire frame and having a lower edge terminating a substantial distance above said bottom, and tool holding elements carried by said slip-over pocket.
